UNITED STATES PATENT OFFICE.

CALVIN B. ROE, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A SANDWICH TRAY OR SIMILAR ARTICLE.

Application filed January 7, 1924. Serial No. 8,260. Term of patent 14 years.

To all whom it may concern:

Be it known that I, CALVIN B. ROE, a citizen of the United States of America, and resident of Moundsville, county of Marshall, and State of West Virginia, have invented a new, original, and ornamental Design for Sandwich Trays or Similar Articles, of which the following is a specification, reference being had to the accompanying drawings, in which—

I claim—

The ornamental design for a sandwich tray or similar article as shown.

CALVIN B. ROE.
